[57] CLAIM

The ornamental design for a end closure for a container, as shown and described.

DESCRIPTION

FIG. 1 is a perspective view of a first embodiment of the end closure for a container;

FIG. 2 is a top plan view thereof;

FIG. 3 is a cross-sectional view taken along line 3—3 of FIG. 2;

FIG. 4 is a perspective view of a second embodiment of the end closure for a container;

FIG. 5 is a top plan view thereof;

FIG. 6 is a cross-sectional view taken along line 6—6 of FIG. 5;

FIG. 7 is a perspective view of a third embodiment of the end closure for a container;

FIG. 8 is a top plan view thereof; and,

FIG. 9 is a cross-sectional view taken along line 9—9 of FIG. 8.
